UNITED STATES PATENT OFFICE.

JOSEPH ISAAC ROBERTS, OF PRESCOTT, ARIZONA.

DEVICE FOR ARCHING AND FITTING SEMI-ELLIPTIC SPRINGS.

1,353,272.

Specification of Letters Patent. Patented Sept. 21, 1920.

Application filed February 28, 1919. Serial No. 279,764.

To all whom it may concern:

Be it known that I, JOSEPH I. ROBERTS, a citizen of the United States, and a resident of Prescott, in the county of Yavapai and State of Arizona, have invented certain new and useful Improvements in Devices for Arching and Fitting Semi-Elliptic Springs, of which the following is a specification.

My invention relates to improvements in devices for forming and shaping semi-elliptic springs, and it consists in the constructions, combinations and arrangements herein described and claimed.

An object of my invention is to provide a device adapted more particularly for use in the blacksmith's shop, whereby the leaves of semi-elliptic springs can be readily made.

Other objects and advantages will appear in the following specification, reference being had to the accompanying drawings in which:

Figure 1 is a side elevation of the device showing a spring clamped in position prior to the initial step in forming,

Fig. 2 is a side elevation illustrating a part of the initial step in forming the leaf,

Fig. 3 is a side elevation showing the parts under another adjustment and in position for finishing the leaf,

Fig. 4 is a perspective view of the central arching frame,

Fig. 5 is a vertical cross section of the arching frame,

Fig. 6 is a sectional view of one of the movable clamp frames, and

Fig. 7 is a perspective view of one of the pressers.

Although the device is capable for use in other associations, it is intended primarily for use in the blacksmith's shop where calls are frequently made to replace semi-elliptic springs. The invention is of such a nature that the leaves of the spring can be readily arched and fitted, and requires but the efforts of two men to operate the pressers which form the leaves of the spring. Therefore in carrying out the invention I provide

The frame 1

which is in the nature of a metal trestle with legs 2 and a top bar 3. Although the trestle is here shown in the conventional form, it may be made in any manner to suit the particular purpose, so long as the top bar 3 is provided for the support of the forming devices. Describing these in regular order,

attention is first directed to the construction of

The arching frame 4

in the middle of the top bar 3. As shown in Fig. 4, the arching frame includes rear and front clamp bars 5 and 6. The front clamp bar 6 branches out into a pair of legs 7 which are confined in bearings 8 against a boss 9 which is integrally formed beneath the top bar 3.

Similarly, the rear clamp bar 5 slides in a slot 10, and thus the clamp bars are guided in the vertical adjustment of the arching frame. Fixed on top of the clamp bars 5 and 6 is the lower member 11 of a clamp in which the leaves 12 and 13 are held in position on the arching frame. A clamp screw holder 14 is hinged at 15 to one end of the member 11. A clamp screw 16 occupies the threaded bore of a boss in the clamp screw holder. A clamp tie 17 is hinged on the opposite end of the lower member 11, and has side fingers giving it a substantial T shape as shown in Fig. 4. The clamp tie 17 is arranged to fit in the bifurcated end of the clamp screw holder 14 so as to hold the ends of the clamp together when applying the clamp screw 16.

Formed in the lower end of the clamp screw 16 is a recess into which the pin 18 on the upper end of an adjusting screw 19 is arranged to enter upon clamping the leaves 12 and 13 in place in the clamp. The upper end of the adjusting screw 19 is fixed in the lower member 11 of the clamp from where it extends down through a smooth hole in the top bar 3 as clearly shown in Fig. 5.

The leaf clamp is adjusted up and down with respect to the top bar 3, by means of a pair of bevel gears 20 and 21. The gear 20 is journaled in a bearing 22 on top of the bar 3, while the gear 21 is journaled in a bearing 23 which is substantially a continuation of the bearing 8 as shown in Fig. 4. A handle 24 serves to turn the gear 21, and consequently the gear 20, when it becomes necessary to adjust the leaf clamp up or down as just stated.

A gage cooperates with the arching frame for the purpose of determining the amount of depression and elevation of the arching frame in initially arching and finally finishing a spring leaf, as will appear more fully later. This gage comprises a graduated

standard 25 which is fixed in respect to the adjustable clamp bars 5 and 6. One of the legs 7 of the front clamp bar 6 has an adjustable pointer 26 which moves over the standard 25. In initially arching a leaf, such as the one 13, the arching frame is lowered a certain number of degrees by counter-rotating the handle 24, and the amount of lowering of the arching frame is regulated by consulting the gage. Similarly, in finally finishing the spring leaf as in Fig. 3, the gage is again consulted in order to determine the number of degrees of elevation of the arching frame in the finishing operation.

The clamping frames.

There are two of the clamping frames 27, one at each end of the top bar 3 as clearly shown in Figs. 1, 2 and 3 of the drawings. Since the construction of both of the clamping frames is alike, the description of one will suffice for both. The clamping frame has a pair of standards 28 of which one is taller than the other. The side members of the clamping frame are held in spaced relationship by a pair of spacer bolts 29. A bridge 30 also spans the two side members and forms a rest for the finger 31 of a tongs 32 which is pivoted on a bolt 33 near the top of the shorter one of the two standards 28.

The bridge 30, as well as the bolt 33, provides an additional spacer for the two side members of the clamp frame 27. Rollers 34 journaled on the clamp frames, bear on the top and bottom surfaces of the bar 3. The clamp frame 27 is adjustable or rather movable along the top bar 3 toward the central arching frame 4. The position of the clamping frames 27 with respect to the arching frame 4, is changed when the final finishing operation of the formed spring leaf as illustrated in Fig. 3, takes place. The upper ends of the standard 28 have non-circular holes 35 into which pins 36 of a corresponding non-circular cross section, are fitted. These pins are adapted to support

The presser 37

in either of two positions on the clamp frame 27. The presser 37 consists of a yoke-shaped frame 38 with a pair of aligned non-circular notches 39 in the lower edge. The presser is seated on the pins 36 by means of these notches. A presser roller 40 is journaled in the frame 38, and the axle of the roller extends out at one side to receive the handle 41 by means of which the roller 40 is turned and by means of which the presser 37 is conveyed over the spring leaf in the forming operation. A clamp roller 42 is journaled in the ends of arms 43 which are loosely hung at 44 on the presser frame 38 as clearly shown in Fig. 7.

While the operator bears down on the

handle 45 of the presser frame 38, the clamp roller 42 is tightly bound against the lower and form leaf 12 as shown in Fig. 2. When the handle 41 is now turned, the presser roller 40 rides over the spring leaf 13 and "irons" it down into the shape of the form leaf 12. The other side is handled in a similar manner by another operator so that the spring leaf 13 is shaped at both ends at the same time.

The handles of the tongs 32 are clamped together by a loop 46 in order to hold the ends of the form leaf 12 in place as shown in Figs. 1 and 2. The purpose of the finger 31 of the upper handle of the tongs is, to keep the lower jaw of the tongs in the one position and prevent its displacement.

The operation.

At the beginning of the operation of forming a spring leaf, the clamp frames 27 are located nearer the extremities of the top bar 3 as shown in Figs. 1 and 2, than they are located on the top bar 3 in performing the finishing operation as illustrated in Fig. 3. A form leaf 12 is clamped in place between the jaws of the tongs 32 of each of the clamp frames 27. The form leaf has a hole in the center which fits over the pin 18 of the adjusting screw 19.

The straight bar 13 of which a spring leaf is to be made, also has a central hole which is fitted on the pin 18. The clamp screw 16 is now screwed down so that the recess in the lower end of the clamp screw receives the upper end of the pin 18. The clamp screw when screwed down, binds tightly upon the bar 13 and holds it securely in place. Each of the pressers 37 is now taken and set upon the ends of the bar 13. To do this, it may be necessary to slightly flex the ends of the bar 13 in order to enable the setting of the presser thereupon.

Each operator then bears down upon the handle 45 of the respective presser, as illustrated at the left in Fig. 2. This results in a clamping action on the bar 13 and this clamping action is obtained by the loosely hung clamping roller 42. The handle 41 is now grasped by the right hand and is turned. This causes the roller 40 to roll over the bar 13 and practically "iron" it down into the shape of the form leaf 12. In order to obtain the proper shape of the spring leaf 13, it becomes necessary to slightly lower the arching frame 4 by means of the handle 24. This is done by slightly counter-rotating the handle and the amount of lowering of the arching frame is regulated by consulting the gage at the left side.

The finishing and fitting operations of the initially formed spring leaf, are completed by transferring the members to the taller of the two standards 28 as shown in Fig. 3.

Fig. 3. This is done by raising the arching frame as shown, and moving the clamp frames 27 inwardly. The ends of the members 12 and 13 are held down beneath the upper non-circular pins 36 and the presser frames 38 are likewise supported on these pins. Should it be necessary to again carry the pressers 37 over the formed member 13, they are simply led out thereupon and the same "ironing" action is performed as before.

While the construction and arrangement of the device as herein described, is that of a generally preferred form, obviously modifications and changes may be made without departing from the spirit of the invention or the scope of the claims.

I claim:

1. A portable spring-leaf forming device, comprising a trestle, a form, clamp frames movable on the trestle and having means for gripping the ends of the form, and including means for supporting the ends of the form when the latter is elevated for the spring leaf finishing operation and when the clamp frames are moved inwardly, central supporting means for the form comprising an arching frame, adjustable means embodied in the arching frame for clamping the form and a leaf bar in position prior to the forming operation, and manually operable pressers associated with the clamp frames, including a presser frame with a presser roller for engaging the leaf bar, a loosely hung clamp roller for engaging the form to obtain the clamping action, an operating handle attached to each presser frame, and a handle for turning the presser roller to accomplish the forming operation.

2. A portable spring-leaf forming device, comprising a trestle, a form, clamp frames movable on the trestle and having means for gripping the ends of the form, including means for supporting the ends of the form when the latter is elevated for the spring leaf finishing operation and when the clamp frames are moved inwardly, central supporting means for the form comprising an arching frame, adjustable means embodied in the arching frame for clamping the form and a leaf bar in position prior to the forming operation, manually operable pressers associated with the clamp frames, including a presser frame with a presser roller for engaging the leaf bar, a loosely hung clamp roller for engaging the form to obtain the clamping action, an operating handle attached to each presser frame, a handle for turning the presser roller to accomplish the forming operation, and means embodied in the arching frame for making adjustments during the forming operation, said means including a graduated standard and a pointer.

3. In a device for forming semi-elliptic springs, an arching frame, fixed in respect to the top bar of a trestle, a clamp including a fixed and a hinged member, means for closing one side of the clamp, clamping means carried by the hinged member, clamp bars dependent from the fixed clamp member, bearing means on the top bar for said clamp bars, an adjusting screw pendent from the fixed clamp member and having a pin projecting above the fixed clamp member to coact with said clamping means, and means journaled in a portion of the arching frame for raising and lowering the adjusting screw and clamp bars together, said means including gears, one of the gears having threaded engagement with the adjusting screw.

4. In a device for forming semi-elliptic springs, an arching frame fixed in respect to the top bar of a trestle, a clamp including a fixed and a hinged member, means for closing one side of the clamp, clamping means carried by the hinged member, clamp bars pendent from the fixed clamp member, bearing means on the top bar for said clamp bars, an adjusting screw pendent from the fixed clamp member and having a pin projecting above the fixed clamp member to coact with said clamping means, means journaled in a portion of the arching frame for raising and lowering the adjusting screw and clamp bars together, said means including gears, one of the gears having threaded engagement with the adjusting screw, and means for gaging the adjustment of said adjusting screw within a narrow limit, including a fixed graduated standard and an adjustable pointer on a portion of one of the clamp bars.

5. Means for gaging the adjustments of an arching frame within a narrow limit at any of the major adjustments thereof, comprising an adjustable arching frame mounted on the top bar of a trestle and including clamp bars, means for adjusting the arching frame including a screw and revolute means arranged to advance the screw, bearings for the clamp bars, a graduated standard fixed on one of the bearings, a pointer slidable on one of the clamp bars, and a thumb screw enabling the loosening of the pointer and shifting thereof to keep it within the zone of the graduated standard at any of the adjustments of the arching frame in the bearing.

6. In a device for forming semi-elliptic springs, a clamp frame comprising side members arranged to flank the top bar of a trestle, said side members having short and long standards provided with non-circular holes near the top, rollers disposed between the side members and engaging the top and bottom surfaces of said top bar, spacing means for the side members includ-

ing a bridge, tongs pivoted on the short standard and including a finger resting on the bridge, and pins non-circular in cross section fitted in said openings, and arranged to support a presser in either of two positions.

- 5 7. In a device for forming semi-elliptic springs, a presser comprising a frame having alining non-circular notches for receiving the non-circular supporting pins of a clamp frame, a presser roller journaled in the frame and having a turning handle, a presser handle attached to the frame, a clamp roller, and clamp roller supporting arms pivotally mounted on said frame.
- 10 8. In a semi-elliptic spring forming device, a central arch support carrying a form member for holding a leaf bar, and means for clamping the leaf bar and form member

in place on the arch support, comprising a lower clamp with a screw holder movably mounted at one end of the clamp, and a clamp tie at the other, and a central clamp screw for engaging the leaf bar when in position on the form, and the clamp tie is 25 swung against the screw holder.

9. In a spring forming device, a presser frame with a handle to be borne on by the operator, a relatively fixed presser roll with a handle for turning it, and a companion 30 presser roll with a swinging mounting on the frame.

10. Arching frame guide means, comprising in combination with a top bar having a slot and bearings, a pair of clamp bars, one 35 occupying the slot, the other branching into legs occupying the bearings.

JOSEPH ISAAC ROBERTS.
